UNITED STATES PATENT OFFICE.

JULIUS P. HEIL, OF MILWAUKEE, WISCONSIN.

FLUID HOIST.

Application filed November 1, 1920. Serial No. 421,175.

To all whom it may concern:

Be it known that I, JULIUS P. HEIL, a citizen of the United States, and resident of Milwaukee, in the county of Milwaukee, 5 and State of Wisconsin, have invented new and useful Improvements in Fluid Hoists, of which the following is a description, reference being had to the accompanying drawings, which are a part of this specification.

10 This invention relates to improvements in fluid hoists.

It is one of the objects of the present invention to provide a fluid hoist more particularly, although not solely adapted for 15 operating the dump bodies of power driven trucks.

A further object of the invention is to provide a fluid hoist which may be easily used in connection with any standard make of 20 truck and dump body, and which will not require any space between the forward end of the body and the cab or seat of the truck.

A further object of the invention is to provide a fluid hoist which will permit the 25 positioning of the body with relation to the front and rear axles to more evenly distribute the load thereon and thereby increase the capacity of the truck.

A further object of the invention is to 30 provide a fluid hoist in which the use of outside pipes or ducts is eliminated.

A further object of the invention is to provide a fluid hoist which is a unitary structure and is self contained and has therefore a minimum number of parts and 35 may be easily mounted on a truck.

A further object of the invention is to provide a fluid hoist which will automatically stop the further tilting of the truck body when said body reaches its predetermined dumping inclination.

A further object of the invention is to provide a fluid hoist in which the piston controls its own movement without stopping the operation of the pump and will 45 automatically stop when the dump body of the truck reaches its predetermined unloading angle even though the pump continues to operate.

A further object of the invention is to 50 provide a fluid hoist in which the dump body of the truck may be maintained in its upper position for an indefinite period while the pump and connected parts continue to operate without injury to the hoist.

55 A further object of the invention is to

provide a fluid hoist in which a single cylinder and piston are used for tilting the dump body.

A further object of the invention is to 60 provide a fluid hoist in which the piston itself serves to automatically stop the supply of the fluid medium to the pump when the said piston reaches a predetermined position of rest.

A further object of the invention is to 65 provide a fluid hoist which is of simple construction, is strong and durable and is well adapted for the purpose described.

With the above and other objects in view, 70 the invention consists of the improved fluid hoist and its parts and combinations as set forth in the claims, and all equivalents thereof.

In the accompanying drawings in which 75 the same reference characters indicate the same parts in all of the views:

Fig. 1 is a side view of the rear portion of a motor truck provided with the improved fluid hoist, parts being broken away 80 and the body portion being shown in tilted position by dotted lines;

Fig. 2 is a transverse sectional view, on a larger scale, taken on line 2-2 of Fig. 1; 85

Fig. 3 is a vertical sectional view taken on line 3-3 of Fig. 2.

Referring to the drawings, the numeral 5 indicates a portion of a motor truck, 6 the side members of the frame or chassis, 7 90 the cab or seat portion and 8 the tilttable load carrying body of the truck. Said body near its rear end portion is pivotally connected to the opposite outer side members 6 by a pivot and bracket means 9.

The improved fluid hoist comprises a cylinder 10 having at its upper opposite sides outwardly projecting portions 11 having aligned trunnion recesses 11' for pivotally receiving the inwardly projecting trunnions 12 of the brackets 13 which rest on and are bolted to the outer side members 6 of the chassis. The cylinder is pivotally supported on said trunnions and depends downwardly therefrom and is provided with a piston 105 14 reciprocally positioned therein. The piston is mounted on the lower end portion of a rod or tube 15 which extends upwardly through the upper closed end of the cylinder and is provided with an upper eyed end 16. 110 Said upper eyed end is pivotally connected to the truck body beneath the bottom por-

- tion by a pivot rod 17 which extends transversely of said bottom portion and into bearing members 18 mounted on longitudinal reinforcing channel members 19 thereof.
- 5 The pivotal connections of the cylinder and the piston rod permit the rod and cylinder to tilt and aline with said pivotal connections while the truck body is traveling through its arc of movement to an inclined
- 10 unloading position.

The cylinder is formed with lower ports 20 and 21 and upper ports 22 and 23 through which the fluid medium flows in passing from one side of the piston to the other.

15 The port 20 is in communication with duct 24 which is formed in the front wall of the cylinder and leads upwardly from said port 20 to a pressure duct 25 and the said duct 25 and the port 22 extend outwardly and 20 into a gear pump 26 mounted on the upper front portion of the cylinder 10, and serve respectively as the inlet and outlet openings to said pump. The duct 25 is provided with a ball check valve 25' which opens 25 downwardly to stop the movement of the fluid medium in the opposite direction. One of the gears 27 of the pump 26 is connected to the transmission gearing 28 of the motor vehicle by a shaft 29 and the two 30 pump gears are rotated thereby. The rotation of said shaft 29 is controlled by a lever 30 positioned within cab 7. The opposite side portion of the cylinder 10 is also provided with a duct 31 which leads upwardly 35 from the discharge port 21 and connects with a manually controlled valve 32 which is mounted transversely on the rear upper portion of the cylinder. The port 23 also connects with the valve 32 and when said 40 valve is in open position the fluid medium can pass upwardly through the duct 31, the valve 32, the duct 23 and into the cylinder above the piston to permit the piston to descend and lower the dump body. As the 45 valve 32 may be opened to a greater or less extent, the speed of the downward movement of the piston may easily be controlled by turning the valve to the desired extent. Said valve is controlled from the cab by a 50 lever 33 having a rod connection 34 with the valve arm 35.

The upper ports 22 and 23 are diametrically opposite each other and are positioned a short distance below the upper end or 55 head of the cylinder, the port 23 being closer to the head than the port 22, so that when said piston is in its upper position it will close the port 22 and partly close the port 23 and automatically stop the supply of fluid medium 60 to the pump and further movement of the piston upwardly, even though the pump gears continue to rotate as they will merely churn the fluid medium and cannot force any more into the cylinder beneath the 65 piston.

As considerable space within the cylinder is required to accommodate the piston rod or tube when in its inner position, less fluid medium is used when the piston is in its inner position than when in its outer position and to supply the varying amounts a tank 36 is mounted on the upper end or head portion of the cylinder and is in communication with the upper end portion of the cylinder by an opening or port 37. The 70 surplus fluid medium is forced upwardly into the tank by the downward movement of the piston rod and flows by gravity from the tank to the cylinder when the piston rod is moved upwardly.

In use the fluid hoist is mounted on a motor truck in the manner shown in Fig. 1, and when it is desired to dump the contents of the truck body the transmission controlling lever is operated to transmit 75 motion from the transmission to the pump and the operation of the pump will draw the fluid medium from above the piston and force it into the cylinder below the piston and force said piston upwardly. 80 The upward movement of the piston will tilt the truck body and unload the contents thereof. When the piston reaches its uppermost position it will close the port 22 and partly close the port 23 and thus automatically shut off the supply of fluid medium or oil to the pump. The pump may continue to operate but as its supply of oil is cut off, it cannot pump any more oil into the cylinder beneath the piston and the upward 85 movement of the piston will automatically stop. This feature is very desirable as it eliminates any danger of damage to the hoist in the event that the operator inadvertently neglects to stop the operation of 90 the pump. The piston will remain in its upper position whether or not the pump is in operation. If it is now desired to lower the truck body the valve rod 34 is operated to open the valve 32 and when opened, the 95 oil in the cylinder below the piston can flow upwardly through the duct 31 and the valve and through the partly opened upper port 23 back into the cylinder above the piston and thus permit the valve controlled descent of the piston and the truck body. The 100 port 23 is always sufficiently open to permit the initial flow of the oil to enter the cylinder above the piston when the valve is in open position. The speed of lowering the truck 105 body is controlled by opening or closing more or less the port of the valve.

It is to be understood that one or any number of cylinders may be used without departing from the spirit and scope of the 110 invention.

From the foregoing description it will be seen that the fluid hoist is of very simple construction and may be easily mounted on a motor truck having a tilttable body.

What I claim as my invention is:

1. A fluid hoist, comprising a single cylinder having a pair of ports at opposite end portions, a piston within the cylinder and between the pairs of ports and having a stem extending through one end of the cylinder, ducts on the opposite sides of the cylinder for connecting the ports of the opposite ends together in pairs, means on one side of the cylinder intersecting one of the ducts for moving a fluid medium from one side of the piston to the other to move the piston in one direction to a predetermined position of rest, said position of rest closing one of the ports and automatically stopping the movement of the fluid medium to the moving means without stopping the operation of the moving means, and means on the other side of the cylinder intersecting the other duct for controlling the movement of the fluid medium through the other ports and the movement of the piston to its other position of rest.

2. A fluid hoist, comprising a cylinder having a pair of ports at opposite ends, a piston within the cylinder and between the pairs of ports and having a stem extending through one end of the cylinder, ducts on the opposite sides of the cylinder for connecting the ports of the opposite ends together in pairs, a pump positioned on one side of the cylinder and intersecting one of the ducts for moving a fluid medium from one side of the piston to the other to move the piston in one direction to a predetermined position of rest, said position of rest closing one of the ports and automatically stopping the movement of the fluid medium to the pump without stopping the operation of the pump, and a valve positioned on the opposite side of the cylinder and intersecting the other duct for controlling the movement of the fluid medium through the other ports and the movement of the piston to its other position of rest.

3. A fluid hoist, comprising a cylinder having pairs of ports adjacent its upper and lower ends, a piston within the cylinder and between the pairs of ports and having a stem extending through the upper end of the cylinder, ducts on opposite sides of the cylinder for connecting the upper and lower ports together in pairs, a pump positioned on one side of the cylinder and intersecting one of the ducts, and a valve on the other side of the cylinder intersecting the other duct, said piston in its upper position of rest closing the upper port of the duct intersected by the pump.

4. A fluid hoist, comprising a cylinder having pairs of ports adjacent its upper and lower ends, a piston within the cylinder and between the pairs of ports and having a stem extending through the upper end of the cylinder, ducts positioned on opposite sides of

the cylinder for connecting the upper and lower ports together in pairs, a pump positioned on one side of the cylinder and intersecting one of the ducts, and a valve on the other side of the cylinder intersecting the other duct, said piston in its upper position of rest closing the upper port of the duct intersected by the pump and partly closing the other upper port.

5. A fluid hoist, comprising a cylinder having pairs of ports at its upper and lower ends, one of said upper ports being in a higher horizontal plane than the other, a piston within the cylinder and between the pairs of ports and having a stem extending upwardly through the upper end of the cylinder, ducts on opposite sides of the cylinder for connecting the upper and lower ports together in pairs, a rotary gear pump on one side of the cylinder intersecting one of the ducts, and a valve on the other side of the cylinder intersecting the other duct, said piston when in its upper position of rest closing the lower of the two upper ports to automatically stop the flow of the fluid medium therethrough and the upward movement of said piston.

6. A fluid hoist, comprising a cylinder having two ports in its upper end and two ports in its lower end, said cylinder also having two ducts positioned on opposite sides of the cylinder which connect one of the upper and one of the lower ducts together in pairs, one of said upper ports being in a higher horizontal plane than the other, a piston within the cylinder and having a stem extending through the upper end of the cylinder, a rotary gear pump on one side of the cylinder intersecting the duct extending to the lower of the upper ports for drawing a fluid medium from the cylinder above the piston and forcing it back into the cylinder beneath the piston, a check valve within the duct between the pump and the lower port in the cylinder connected to said duct, and a valve on the other side of the cylinder for intersecting the other duct to permit the fluid medium to flow from the cylinder beneath the piston to the cylinder above the piston, said piston when in its upper position of rest closing the lower of the two upper ports to automatically stop the upward movement of the piston.

7. A fluid hoist, comprising a support, a cylinder fulcrumed thereon and having pairs of ports formed in its upper and lower end portions, a piston within the cylinder and between the ports and having a stem extending through the upper portion of the cylinder, a tiltable body positioned above the cylinder and pivotally connected to the upper end portion of the piston stem, ducts positioned on opposite sides of the cylinder for connecting the upper and lower ports together in pairs, one of the upper ports being

in a higher horizontal plane than the other, a power driven gear pump on one side of the cylinder intersecting the duct connected to the lower of the upper ports for drawing a fluid medium from the cylinder above the piston and forcing it back into the cylinder beneath the piston, a check valve within the duct and between the pump and the lower port in the cylinder connected to said duct, 10 a manually operable valve on the other side of the cylinder for intersecting the other

duct to permit the fluid medium to flow from the cylinder beneath the piston to the cylinder above the piston, and a tank for receiving the medium from the cylinder, said piston when in its upper position of rest closing the lower of the two upper ports to automatically stop the upward movement of the piston.

In testimony whereof, I affix my signature.

JULIUS P. HEIL.
